AUTOMATIC FIRE ALARM

Filed Jan. 24, 1931

1 Inventor:
Harold C. Ostrom,
By Charles O. Henry
Atty.

UNITED STATES PATENT OFFICE

HAROLD C. OSBORN, OF PALATINE, ILLINOIS

AUTOMATIC FIRE ALARM

Application filed January 24, 1931. Serial No. 510,953.

This invention relates to automatic fire alarms, and its principal object is to provide an alarm adapted to be set into operation under an increase in temperature considerably above the normal temperature of the place where the alarm is located. Another object is to provide an automatic fire alarm composed entirely of mechanical elements and self-contained as a compact unit, whereby it may be placed in any convenient point in a dwelling or other building.

Sometimes a fire breaks out in a building and the persons therein are unaware of the fire until it has made sufficient headway to endanger the entire building, as well as the lives of the occupants, and an object of this invention is to provide a simple and highly efficient mechanical alarm mechanism which is sensitive to an increase in temperature substantially above the normal temperature in the place in which the alarm is located. Another object is to provide a fire alarm having an alarm sounding device which shall produce a relatively high and shrill sound which is readily distinguishable as a fire alarm and capable of being heard at a considerable distance away from the place where the alarm is installed.

With these and other objects and advantages in view, this invention consists in a fire alarm embodying a spring motor having means controlled by thermostatic changes adapted to actuate an alarm sounding device. It further consists in a fire alarm embodying a spring motor having means for actuating the alarm sounding device and provided with a thermostatic arm acting to prevent operation of the spring motor under normal thermal conditions.

It further consists in the several novel features hereinafter set forth and claimed.

The invention is clearly illustrated in the drawings accompanying this specification in which—

Figure 1 is a front elevation, partly in vertical longitudinal section, of an automatic fire alarm illustrating one embodiment of the present invention; and

Fig. 2 is a vertical cross section taken on the line 2—2 of Fig. 1.

Referring to said drawing, the reference character 3 designates a case or cabinet, the walls of which are preferably formed of open work or perforated material. As shown, the case is rectangular in form and its four walls, and top and bottom, are provided with perforations. The alarm mechanism is contained in the case and, as shown, comprises, among other things, a spring motor 4 mounted upon the back wall 5 of the case. The spring motor may be of any desirable form having the usual spiral spring 6, one end of which is secured to the winding arbor 7 and the other end to a drum connected with a gear wheel 8 which is the first of a train of speed increasing gears carried by arbors journaled in the side plates 9 of the spring motor.

Mounted upon the arbor 10 of the last member of the train of gears is a rotatable member, which may be regarded as one element of the train of gears and here shown in the form of a toothed wheel 11, with which engages a thermostatic arm 12, here shown as supported by one of the side plates 9 of the spring motor. As is well known, the thermostatic arm 12 is composed of two metals having different co-efficients of expansion, and, as shown, is of curved form, whereby when subjected to an increase in temperature, the arm tends to straighten and moves out of engagement with the toothed wheel 11. The arm may take the form of a detent, its curved end 13 engaging with a tooth of the toothed wheel 11, and its other end being curved upon itself, as shown at 14, and secured to a bracket arm 15 screwed or otherwise fastened to one of the side plates 9 of the spring motor.

Under normal thermal conditions, the free end of the thermostatic arm 12 is held in engagement with one of the teeth of the toothed wheel 11, thereby preventing the spiral spring from unwinding and operating the train of gears. Under an abnormal increase in temperature, however, the thermostatic arm 12 tends to straighten, thereby releasing the toothed wheel 11 and permitting the spiral spring to operate the train of gears of the spring motor.

Supported within the case, as, for instance, upon the side plates 9 of the spring motor is a sound producing device 16, such as a horn having a diaphragm 17 at its smaller end which is provided with a vibratory tongue 18 on its outer side that engages with the teeth of a toothed wheel 19 which may be one of the gear wheels of the train of gears of the spring motor. Whenever the toothed wheel 19 is rotated rapidly, it acts on the tongue with a wiping action and as a result the tongue 18, and consequently the diaphragm 17 is vibrated, thereby producing a very shrill piercing sound which is audible at a considerable distance away from the place where the alarm is located.

The thermostatic arm is adjusted to remain inactive under normal thermal conditions, and for an ordinary dwelling or other building is adjusted to remain in engagement with the toothed wheel 11 so long as the temperature at the alarm device remains below 110° Fr., or thereabouts. In certain situations, this may be altered, so that the thermostatic arm remains inactive until the temperature reaches a point considerably above 110° Fr.

In the operation of the device, the alarm is placed upon a suitable support, or is suspended from a wall or other part of a room in the building, and the spring is wound up, so that the spring motor will be ready for operation in case the toothed wheel 11 becomes free to rotate. In case a fire breaks out, as soon as the temperature of the room wherein the fire alarm is contained reaches 110° Fr., the thermostatic arm has straightened out sufficiently to become disengaged from the toothed wheel 11, thereby permitting the entire train of gears to rotate. As a result, the toothed wheel 19 vibrates the tongue 18 and diaphragm 17 very rapidly, thereby producing a shrill piercing sound which is audible at a considerable distance away from the place where the alarm is located, and the attention of persons is thereby attracted to the place where the fire is located.

More or less variation of the exact details of construction is possible without departing from the spirit of this invention. I desire, therefore, not to limit myself to the exact form of the construction shown and described, but intend, in the following claims to point out all of the invention disclosed herein.

I claim as new, and desire to secure by Letters Patent:

1. An automatic fire alarm comprising in combination an alarm sounding device including a spring motor having a train of speed increasing gears, and a thermostatic element anchored at one end, its other end engaging the last element of the train of

gears and normally preventing operation of the spring motor under normal thermal conditions.

2. An automatic fire alarm comprising in combination an alarm sounding device including a spring motor having a train of speed increasing gears, one of the last gears of said train co-operating with the alarm sounding device to sound an alarm, and a thermostatic arm normally engaging an element of said spring motor to prevent operation thereof under normal thermal conditions. 70

3. An automatic fire alarm comprising in combination an alarm sounding device including a spring motor having a train of speed increasing gears, and a thermostatic arm normally acting as a detent engaging one of the elements of said train of gears to prevent rotation thereof under normal thermal conditions. 80

4. An automatic fire alarm comprising in combination a spring motor having a train of speed increasing gears, a thermostatic arm for preventing operation of the spring motor under normal thermal conditions, and an alarm sounding device having a diaphragm adapted to be vibrated by one of the last gears of the train. 90

5. An automatic fire alarm comprising in combination a spring motor having a train of speed increasing gears, a thermostatic arm normally engaging a rotatable member of the spring motor and serving to prevent rotation thereof under normal thermal conditions, and an alarm sounding device having a diaphragm adapted to be vibrated by said one of the last gears of said train. 100

6. An automatic fire alarm comprising in combination a spring motor having a train of gears and a toothed wheel driven by the last element of the train of gears, a thermostatic arm engaging said toothed wheel and serving to prevent rotation thereof under normal thermal conditions, and a sound amplifier having a diaphragm adapted to be vibrated by one of the last gears of said train. 105

7. An automatic fire alarm comprising in combination a spring motor having a rotatable high speed toothed diaphragm-actuating member, a thermostatic arm normally engaging one of the rotatable members of said spring motor, and a sound amplifier including a diaphragm having a vibratory tongue projecting therefrom and engaging with the teeth of said diaphragm-actuating member, the teeth of said member acting on the tongue with a wiping action. 115

8. An automatic fire alarm comprising in combination a spring motor having a train of gears, a thermostatic arm acting to prevent operation of said spring motor under normal thermal conditions, and a sound amplifier including a diaphragm having a vi- 120

bratory tongue projecting therefrom and engaging with the teeth of one of the last gears of said train of gears, the teeth of said tongue engaging gear acting thereon with a wiping action.

5. 9. An automatic fire alarm comprising in combination a spring motor having a train of gears, a toothed member driven by the last element of the train of gears, a thermostatic arm serving as a detent engaging said toothed member under normal thermal conditions, and an amplifier including a diaphragm having a vibratory tongue engaging with one of the last gears of the train of gears, the teeth of said gear acting thereon with a wiping action.
